UNITED STATES PATENT OFFICE.

WILLIAM ROWBOTTOM AND JOHN M. ROWBOTTOM, OF ALLEGHENY, PA.

CESSPOOL-WELL.

SPECIFICATION forming part of Letters Patent No. 292,953, dated February 5, 1884.

Application filed June 22, 1883. (No model.)

To all whom it may concern:

Be it known that we, WILLIAM ROWBOTTOM and JOHN M. ROWBOTTOM, of Allegheny city, in the county of Allegheny and State of Pennsylvania, have invented a new and useful Improvement in Cesspool-Well; and we do hereby declare the following to be a full, clear, and exact description thereof.

As heretofore usually constructed, cesspool-wells have been made with the pipe which connects with the sewer running directly into the well. This construction has been found very objectionable, because the coarser matters in the well have clogged the mouth of the pipe and stopped the discharge from the well, causing it to fill up rapidly and require frequent cleaning. It has been suggested to cover the mouth of the pipe with a grating or screen, also placed in the well. The purpose of our invention is to obviate this objection and construct the well with an external chamber extending up the side, and provided with a grating between the well and chamber, and having the discharge-pipe opening into the chamber, so that the coarser matters will be prevented from obtaining access to the mouth of the discharge-pipe.

To enable others skilled in the art to make and use our invention, we will now describe it by reference to the accompanying drawings, in which—

Figure 1 is a vertical section, and Fig. 2 a cross-section on the line $x x$ of Fig. 1.

The well a is constructed in the usual way. Connected to it is a chamber, b , of any desired size, and communicating with the well a by means of an opening, c , in which there is a grating, d , of any desired construction, having

the interstices between the bars of the required size to prevent the passage of the larger matters in the well to the chamber. The inner end of the discharge-pipe e terminates in the chamber b , and its outer end runs down to a sewer, f , in the usual way. By this arrangement the larger matters, such as are liable to clog the discharge-pipe, are prevented from obtaining access to it, so that the well is at all times properly drained, and there is no danger of the pipe becoming clogged.

It is admitted that prior to our invention sinks and similar structures having gratings and perforated division-walls for preventing the clogging of the end of the soil-pipe had been devised. It is also admitted that privy-wells having a screen or grating over the end of the soil-pipe are old, and we disclaim such constructions.

We do not limit ourselves to any particular form or construction of the chamber b and grating d , but claim them, broadly, in connection with a cesspool-well.

What we claim as our invention, and desire to secure by Letters Patent, is—

The combination of the well a with the auxiliary chamber b , grating d , discharge-pipe e , and sewer f , substantially as and for the purposes described.

In testimony whereof we have hereunto set our hands this 20th day of June, A. D. 1883.

WILLIAM ROWBOTTOM.
JOHN M. ROWBOTTOM.
